TRAY WASHING AND STERILIZING
MACHINE

Charles M. O'Connor, Tucson, Ariz.

Continuation of application Serial No. 260,481,
December 7, 1951. This application January 19,
1953, Serial No. 332,034

8 Claims. (Cl. 15—56)

1

This application is a continuation of my co-pending application Serial No. 260,481, filed December 7, 1951, now abandoned.

This invention relates to washing machines, and more particularly to a machine for washing and sterilizing cafeteria trays.

A main object of the invention is to provide a novel and improved tray washing and sterilizing machine which is simple in construction, which is relatively compact in size, and which is adapted to thoroughly scrub and cleanse cafeteria trays in a rapid and economical manner.

A further object of the invention is to provide an improved automatic washing and sterilizing apparatus for cafeteria trays, said apparatus being inexpensive to fabricate, involving relatively few parts, being economical in the use of soap and water, and providing a thorough cleansing and sterilizing action.

Another object of this invention is to provide an improved automatic washing and sterilizing apparatus in which scrubbing and rinsing devices serve to feed the trays through the machine and to cause the discharge of the trays from the machine at the completion of the cleaning operations.

Still another object of this invention is to provide an improved tray washing and sterilizing machine in which the trays to be cleaned are moved through the machine by a combination of gravity feed, propulsion by the washing elements of the machine, and jet stream action of the sterilizing elements of the machine in discharging the trays from the apparatus.

Further objects and advantages of the invention will become apparent from the following description and claims, and from the accompanying drawings, wherein:

Figure 1 is a top view of an improved tray washing and sterilizing apparatus constructed in accordance with the present invention.

Figure 2 is a side elevational view of the tray washing and sterilizing apparatus of Figure 1, portions of the side walls of the apparatus being broken away to reveal details of interior construction, and portions of the interior components being shown in vertical longitudinal cross section.

Figure 3 is a rear end elevational view of the tray washing and sterilizing apparatus of Figures 50

2

1 and 2, a portion of the apparatus being shown in vertical transverse cross sectional view.

Figure 4 is a side elevational view of the apparatus of Figures 1 to 3, taken from the side opposite to that in which the view of Figure 2 is taken.

Figure 5 is a vertical transverse cross sectional view taken on the line 5—5 of Figure 2.

Figure 6 is a fragmentary vertical transverse cross sectional view taken on the line 6—6 of Figure 2.

Referring to the drawings, the improved tray washing and sterilizing machine is designated generally at 11 and comprises an upstanding generally rectangular housing having the side walls 12 and 13, the end walls 14 and 15, the top wall 16 and the bottom wall 17. Secured transversely in the intermediate portion of the housing is a transverse partition wall 18 defining a washing compartment 19 on one side thereof and a sterilizing compartment 20 on the other side thereof.

The end wall 14 of the housing is formed with a horizontal loading slot 21 located in the upper portion of said end wall 14 and communicating with the tray washing compartment 19. The side wall 12 of the housing is formed in its lower portion with a horizontal discharging slot 22 communicating with the sterilizing compartment 20 located lower down and at right angles to said loading slot. Designated at 23 is an inclined feed guide bar secured longitudinally in the housing adjacent the side wall 13 and extending downwardly from a point immediately subjacent the slot 21, as shown in Figure 2, and extending through the washing compartment 19 and the sterilizing compartment 20. The partition wall 18 is formed with a horizontal slot 24 adjacent the guide bar 23 and arranged to allow the passage therethrough of a tray 25 moving downwardly on the guide bar 23 from the washing compartment 19 to the sterilizing compartment 20.

Secured in the sterilizing compartment 20 are a pair of inclined discharge guide bars 26, 26 extending downwardly from the side wall 13 to the side wall 14 and terminating subjacent the horizontal slot 22, as shown in Figure 6, said inclined guide bar 26 being arranged to guide a tray downwardly and out of the housing through slot 22, as will be subsequently explained.

Designated at 27 are respective groups of rotary

brushes mounted transversely in the washing compartment 19 above and below the plane of the guide bar 23, the shafts of the brushes being journaled in the side walls 13 and 14 and being provided at their ends with the meshing gears 28 disposed adjacent the side wall 13, one of the gears designated at 28' being provided with a sprocket wheel 29 which is coupled by a sprocket chain 30 to a sprocket wheel 31 secured on the shaft of an electric motor 32 mounted on the top wall 16 of the housing.

Designated at 33 is a water trough mounted in the lower portion of the washing compartment 19, and designated at 34 is a gas burner mounted below the trough 33 and connected through a conduit 35 and a control valve 36 to a source of illuminating gas. Mounted in the upper portion of the washing compartment above and below the plane of the guide bar 23 are the respective conduits 37 and 38 having secured thereto the transversely extending apertured spray nozzles shown respectively at 39 and 40 and 41 and 42, said spray nozzles being arranged transversely to the housing and disposed adjacent to the plane of the guide rail 23 and on opposite sides thereof. As shown in Figure 2, the spray nozzles 39 and 40 extend between successive rotary brushes 27 above the plane of the guide rail 23 and the spray nozzles 41 and 42 extend between successive brushes 27 below said plane.

The conduits 37 and 38 are connected to a conduit 43 which is connected through a circulating pump 44 to a conduit 45. The conduit 45 is connected to the lower portion of the water trough 33, as shown in Figure 5.

Mounted in the end wall 14 is a conventional thermometer 46 having its indicator 47a arranged externally with respect to wall 14, as shown in Figure 2.

Designated at 47 is the horizontal screen which is slidably mounted in the intermediate portion of the washing compartment between the lowermost water conduit 38 and the water tank 33, as shown in Figure 2, the screen 47 being readily removable through a slot provided therefor in end wall 14 whenever cleaning of the screen 47 becomes necessary.

Designated at 48 and 49 are respective additional water conduits secured in the sterilizing compartment 20 above and below the plane of the guide bar 23, said conduits 48 and 49 being provided with jet spray nozzles 50 directed toward the plane of said guide rail. The conduits 48 and 49 are connected through a control valve 50a to a conduit 51 leading to a suitable supply of hot water.

The circulating pump 44 is coupled to the shaft of the motor 32 by a conventional coupling 52, as shown in Figure 3, on the side of the motor opposite to the sprocket wheel 31.

In operation, soap and water are placed in the trough 33, the gas burner 34 being ignited so as to elevate the soap and water in trough 33 to the desired washing temperature, as indicated on the dial 47 of thermometer 46. Conventional thermostatic control means may be employed in conjunction with the burner 34 to automatically maintain the temperature of the soap and water at a desired value. Hot water is admitted to the conduits 48 and 49 in the sterilizer compartment 20 by opening the control valve 50. The motor 32 is energized, causing the brushes 27 to revolve and causing the circulating pump 44 to circulate soapy water from the trough 33 through the conduits 37 and 38 and the spray nozzles 39, 40, 41 and 42.

41 and 42. The trays 25 to be cleaned are inserted into the housing through the slot 21, the trays being then scrubbed and propelled through the washing compartment 19 by the rotary action of brushes 27, each tray being simultaneously sprayed with hot soapy water by the nozzles 39 to 42. The tray 25 is then fed through the slot 24 into the sterilizer compartment 20 along the guide bar 23 by the action of the brushes 27 and is subjected to the hot water spray from the nozzles 50, whereby the scrubbed surfaces of the tray are thoroughly sterilized. As soon as the rear margin of the tray becomes disengaged from the slot 24, the tray drops off the guide bar 23 onto the inclined bar members 26, 26 and slides out of the sterilizing compartment 20 through the exit slot 22.

It will be noted that the weight of the tray combined with the force of the hot water sprays acting on the tray causes the tray to drop off of the guide bar 23 onto the inclined bar member 26 and causes the cleaned and sterilized tray to be ejected from the apparatus.

Connected to the bottom wall 17 below the sterilizing compartment 20 is a drain conduit 62 allowing the waste water to leave the apparatus to be drained into the sewer system.

The screen 47 may be periodically cleaned by removing it from the washing compartment 19, as above explained, to dislodge food particles and other waste material therefrom which may have collected thereon during the operation of the apparatus.

If so desired, a suitable supply of water may be connected to the water trough 33 controlled in any conventional manner, as by a float valve, to maintain the level of water in the trough 33 at its optimum value.

While a specific embodiment of an improved tray washing and sterilizing apparatus has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A tray washer and sterilizing machine comprising a housing having side walls, end walls, a top wall and a bottom wall, a transverse partition secured in said housing defining a washing compartment on one side thereof and a sterilizing compartment on the other side thereof, one end wall of the housing being formed with a slot communicating with the washing compartment and one side wall of the housing being formed with a slot communicating with the sterilizing compartment, an inclined guide bar secured longitudinally in said housing adjacent the side wall 60 and extending downwardly from the first named slot into the sterilizing compartment, said partition wall being formed with a horizontal slot adjacent said guide bar, a plurality of rotary transverse brushes mounted above and below the plane of the guide bar, said transverse rotary brushes being disposed in the washing compartment, a water trough in the lower portion of said washing compartment, heating means associated with said trough, spray nozzles above and below the brushes and directed toward the plane of the guide bar, conduit means connecting the water trough to the spray nozzles and including a circulating pump, inclined guide means in the sterilizing compartment below the plane of the 65 guide bar and extending subjacent the second

named slot, additional spray nozzles in the sterilizing compartment, and conduit means connected to said additional spray nozzles and adapted to be connected to a source of hot water.

2. A tray washer and sterilizing machine comprising a housing having side walls, end walls, a top wall and a bottom wall, a transverse partition secured in said housing defining a washing compartment on one side thereof and a sterilizing compartment on the other side thereof, one end wall of the housing being formed with a slot communicating with the washing compartment and one side wall of the housing being formed with a slot communicating with the sterilizing compartment, inclined guide means disposed longitudinally in said housing adjacent a side wall and extending downwardly from the first named slots into the sterilizing compartment, said partition wall being formed with a horizontal slot adjacent said guide means, a plurality of transverse rotary brushes mounted above and below the plane of the guide means in the washing compartment, a water trough in the lower portion of said washing compartment, heating means associated with said trough, spray nozzles adjacent the brushes and directed toward the plane of the guide means, water circulating means connecting the water trough to the spray nozzles, inclined guide means in the sterilizing compartment below the plane of the first named guide means, said last named inclined guide means extending subjacent the second named slot, additional spray nozzles in the sterilizing compartment, and conduit means connected to said additional spray nozzles and adapted to be connected to a source of hot water.

3. A tray washer and sterilizing machine comprising a housing having side walls, end walls, a top wall, and a bottom wall, a transverse partition secured in said housing defining a washing compartment on one side thereof and a sterilizing compartment on the other side thereof, one end wall of the housing being formed with a slot communicating with the washing compartment and one side wall of the housing being formed with a slot communicating with the sterilizing compartment, an inclined guide bar secured longitudinally in said housing adjacent a side wall thereof and extending downwardly from the first named slot into the sterilizing compartment, said partition wall being formed with a horizontal slot adjacent said guide bar, a plurality of transverse rotary brushes mounted above and below the plane of the guide bar in the washing compartment, a water trough in the lower portion of said washing compartment, heating means associated with said trough, spray nozzles above and below the brushes and directed toward the plane of the guide bar, conduit means connecting the water trough to the spray nozzles and including a circulating pump, inclined guide means in the sterilizing compartment below the plane of the guide bar and extending subjacent the second named slot, additional spray nozzles in the sterilizing compartment, conduit means connected to said additional spray nozzles and adapted to be connected to a source of hot water, and a horizontal screen removably mounted in the washing compartment between the rotary brushes and the water trough.

4. A tray washer and sterilizing machine comprising a housing having side walls, end walls, a top wall, and a bottom wall, a transverse partition wall secured in said housing defining a washing compartment on one side thereof and

a sterilizing compartment on the other side thereof, one wall of the housing being formed with a slot communicating with the washing compartment, and the housing being formed with another slot communicating with the sterilizing compartment, inclined guide means disposed in said housing and extending downwardly from the first named slot into the sterilizing compartment, said partition wall being formed with a slot adjacent said guide means, a plurality of transverse rotary brushes mounted above and below the plane of the guide means in the washing compartment, a water trough in the lower portion of said washing compartment, heating means associated with said trough, spray nozzles adjacent the brushes and directed toward the plane of the guide means, water circulating means connecting the water trough to the spray nozzles, inclined guide means in the sterilizing compartment below the plane of the first named guide means and extending subjacent the second named slot, additional spray nozzles in the sterilizing compartment, and conduit means connected to said additional spray nozzles and adapted to be connected to a source of hot water.

5. A tray washing and sterilizing machine having, a housing, a horizontally disposed loading slot in said housing adapted to receive trays to be washed, a horizontally disposed discharge slot located lower down in said housing, an inclined feed guide bar fixed in said housing and extending downwardly from said loading slot toward said discharge slot, rotary brush means in said housing between said slots for scrubbing trays inserted in said loading slot and to cause downward feeding movement of said trays toward said discharge slot, inclined discharge guide bars in said housing positioned between the lower end of said inclined feed guide bar and said discharge slot, soap and water supply means associated with said rotary brush means, and sterilizing water supply means located above said discharge guide bars.

6. A tray washing and sterilizing machine having, a housing, a horizontally disposed loading slot in said housing adapted to receive trays to be washed, a horizontally disposed discharge slot located lower down in said housing, an inclined feed guide bar fixed in said housing and extending downwardly from one end of said loading slot toward said discharge slot, a series of rotary brushes mounted in said housing behind said loading slot, means for driving said brushes to cause feeding of said trays along said feed guide bar toward said discharge slot, inclined discharge guide bars located at right angles to said feed guide bar adapted to receive trays from said feed guide bar and discharge them out through said discharge slot.

7. A tray washing and sterilizing machine having, a housing, a horizontally disposed loading slot in said housing adapted to receive trays to be washed, a horizontally disposed discharge slot located lower down in said housing, an inclined feed guide bar fixed in said housing and extending downwardly from one end of said loading slot toward said discharge slot, a series of rotary brushes mounted in said housing behind said loading slot, means for driving said brushes to cause feeding of said trays along said feed guide bar toward said discharge slot, inclined discharge guide bars located at right angles to said feed guide bar adapted to receive trays from said feed guide bar and discharge them out through said discharge slot, sterilizing water discharge jets located above said discharge guide bars to eject

liquid against said trays to cause them to be tipped from said feed guide bar and to be received by said discharge guide bars.

8. In a tray-washing and sterilizing machine, a housing, a loading slot, a downwardly sloping feed guide bar in said housing located to one side of said loading slot, scrubbing and feeding brushes behind said slot having their working portions in alignment with said feed guide bar, detergent water supply means associated with said brushes, a plurality of discharge guide bars sloping at substantially right angles to said feed guide bar, a discharge slot in said housing at

the lower ends of said discharge guide bars, and sterilizing jet means above said discharge guide bars.

CHARLES M. O'CONNOR.
